(57) **CLAIM**

The ornamental design for a utility hook, as shown and described.

DESCRIPTION

FIG. 1 is a perspective view of a utility hook;

FIG. 2 is a front plan view thereof;

FIG. 3 is a rear plan view thereof;

FIG. 4 is a side plan view thereof;

FIG. 5 is the other side plan view thereof;

FIG. 6 is a top end view thereof; and,

FIG. 7 is a bottom end view thereof.

The broken lines depict subject matter that forms no part of the claimed utility hook and are provided solely for illustrating the full utility hook.
